UNITED STATES PATENT OFFICE.

MILTON O. SCHUE, OF BERLIN, NEW HAMPSHIRE, ASSIGNOR TO BROWN COMPANY, OF BERLIN, NEW HAMPSHIRE, A CORPORATION OF MAINE.

INDICATOR FOR AUTOMATIC SLOWNESS TESTERS.

Application filed January 23, 1926. Serial No. 83,324.

This invention relates to means for recording continuously the product of two variable quantities during the variation of either, or both, within certain limits. It also relates to mechanism, associated and concurrently operated with the recording means, for keeping constant the ratio of the two variables for controlling a factor or condition on which said ratio depends, as for example, automatically controlling the character of liquid suspensions of solid material.

More specifically, the invention is designed to provide both an improved recorder for use with the automatic slowness tester described in my application Serial No. 721,246, filed June 20, 1924, and also improved means for keeping substantially constant the concentration of an aqueous suspension of cellulosic fibers or material for the testing of which my slowness tester is designed. But it is to be understood that the scope and applicability of the invention are not limited to the particular art or machine in connection with which it is hereinafter more fully explained and described.

As pointed out in the above mentioned application, the quality of "slowness" or its reciprocal "freeness" of an aqueous suspension of cellulosic fibers or other material capable of forming a mat pervious to the suspending liquid is of great importance in the art of paper making, since the quality of the paper will depend in large measure thereon, this being dependent on the degree to which the pulp has been "beaten". The process of beating serves usually to decrease the freeness of the stock and to increase the strength of the paper made therefrom (up to a certain point), to give a more even texture to the paper, and to reduce the probability of the formation of "wild" sheets. Pulp which is beaten behaves as if the process of beating coated the fibers increasingly with a mucilaginous substance, the result being that water flows more readily through pulp which has had less beating. Consequently, the rate of flow through a mat of given thickness is a measure of the freeness of the pulp, other factors affecting the rate of flow being constant. It will be readily understood that any apparatus capable of measuring the freeness of pulp will be equally available for measuring the slowness or resistance to the flow of the liquid by a mere change of scale since the two characteristics

have a simple reciprocal relation to each other. On account of the increase in slowness caused by beating, too much beating will not only result in a waste of energy in running the beater, but will cause the pulp mat to form more slowly on the Fourdrinier screen, thus necessitating either a slower operation of the paper-making machine or a heating of the pulp mixture to reduce the viscosity of the water, with a consequent waste of steam. Another result of beating the pulp beyond the desired point of freeness is that the character of the finished paper will be altered thereby. Hence, for the economical and efficient operation of a paper-making machine, as well as for a uniform product, it is necessary to keep track of and regulate the freeness (or slowness) of the pulp.

In the application mentioned above is disclosed a device for indicating continuously the freeness of a pulp suspension, preferably when passing from a beating engine to a paper-making machine. As therein set forth, freeness may be expressed as the product of the rate of flow of white water (the water which has passed through the mat) by the thickness of the mat, provided the viscosity of the water and the hydraulic head be kept constant or compensated for. Since the viscosity of water varies sharply with the temperature, the temperature and level of the pulp mixture in the vat must be kept constant or reduced to standard.

It is clear that if either the thickness of the mat or the rate of flow of white water is also kept constant, a measure of the other with the proper units will be a measure of the freeness or slowness. It is preferable, however, to provide for concurrent variations in both of these quantities. By using a water-meter of the capillary type, variations in temperature can be disregarded since the mass of capillaries through which the white water passes in such a meter virtually reproduces the porous structure of the pulp mat as far as the viscosity of the water is concerned, so that a change of temperature affecting the viscosity of the water would have similar effects on its flow through the pulp mat and through the capillaries and therefore would not have to be corrected for. It is preferred, however, to use a meter of the orifice type as will be hereinafter described, which type of meter is

relatively unresponsive to changes in viscosity, hence it is important to maintain a constant temperature when using this type of meter.

By the present invention simplified means are provided for continuously recording the product of the two concurrent variables, comprising the rate of flow of white water and the thickness of the mat of pulp formed on a Fourdrinier screen. In the recording device disclosed in the previous application, logarithmic spiral cams were used. It is difficult and expensive to cut such cams with the necessary degree of accuracy. My improved recording device does away with the necessity for such cams and may be constructed of simple and relatively inexpensive parts. The recording device may also be electrically connected to repeat the indications at any desired distance, to control the beating engine or other machinery desired, to give warning signals when the character of the pulp reaches certain limiting conditions, or to perform any combination of the above or other desired functions simultaneously.

By this invention also improved means are provided for regulating the stock density in the vat of the testing apparatus. Since the water supply to the vat must be regulated to maintain a constant level in the vat, the stock density is controlled by varying the rate at which pulp is admitted to the vat from the beating engine. Although the measurements of freeness or slowness in the manner described above are independent of the stock density within comparatively wide limits, yet it is desirable to maintain a reasonable uniformity of stock density in the vat. Mathematical calculation, checked by experimental results, has shown that the stock density is measurable by and proportional to the thickness of the pulp mat divided by the rate of flow of the white water. Novel mechanism is therefore provided according to this invention for regulating the admission of pulp to the vat which is responsive simultaneously to variations in the thickness of the pulp mat and the rate of flow of white water. This results in a stock density in the vat which is fairly constant.

Further advantageous features and combinations will be found in the following description of the device and in the drawings, in which

Figure 1 is a general view in elevation of the recording mechanism and a part of the mechanism for regulating the stock density.

Figure 2 is an elevation of a slowness testing device with which the present invention is adapted for use. A conventional beating engine of the Jordan type is indicated on a reduced scale.

Figure 3 is a perspective of a meter for measuring the flow of the white water.

Figure 4 is a side elevation of the recording device showing also the apparatus for controlling the feed of pulp from the beating engine to the vat of the slowness tester.

Figures 5 to 9 are details of construction hereinafter to be described.

Figure 10 is a sectional view showing the construction of the cylinder on which the pulp mat is formed, and the means for maintaining a constant hydraulic head.

Figure 11 is a transverse section of the cylinder.

Figure 12 is a detail of a "hunting" mechanism used to make the indicating devices respond to variations in the thickness of the pulp mat.

Figure 13 is a diagrammatic showing of the electric wiring used with the recording device.

Figure 14 is a diagrammatic showing of modified form of that part of the wiring system relating to the control of the motors used in the apparatus.

Referring in detail to the drawings, Figure 2 indicates an automatic slowness or freeness testing device for pulp suspensions for use with which the present invention is particularly suited. A brief description of the construction and operation of this tester will be given, but for a more complete showing and description of the details of structure, reference is had to my co-pending application Serial No. 721,246, filed June 20, 1924.

A vat or container 1 for the pulp suspension is suitably located to receive pulp to be tested from the beating engine 2 (which is shown in the drawing for convenience on a reduced scale) through the pipe 3, by which the pulp from the beating engine passes through a sampling box 4 and pipe 5 to the stock chest. A portion of the pulp passing through the sampling box is admitted through a gate valve 6 and passes into the vat through a supply pipe 7. The means for controlling the admission of pulp to the vat will be described later.

In the determination of the freeness of the stock, a mat of pulp is continuously formed on the submerged portion of a horizontal cylinder mold 11, indicated in outline in Figure 2, on the surface of which is a Fourdrinier screen 12, as the cylinder is rotated at a substantially constant speed. The pulp suspension is kept at a constant level to maintain a constant hydrostatic head, the preferred level, as shown in the drawing, bisecting the cylinder. This constant level is preferably maintained by the admission of water through a supply pipe 13, the flow being regulated as by a valve 14 operated by a diaphragm motor 15 controlled by a float 16 and a valve 17, and by

an overflow conduit 8, the mouth 9 of which is positioned on a level with the center line of the cylinder mold 11. The diaphragm motor 15 may be operated by air, or any other suitable fluid under pressure. The float 16 is preferably so adjusted that when the suspension in the vat is at normal level, there will be a small inflow of water through the pipe 13, thereby insuring a constant hydrostatic head and a sufficient circulation of stock in the vat even when the stock is very slow.

The stock in the vat is kept from settling by agitators 18 mounted on a shaft 19 which is driven from any convenient source of power 20.

To facilitate accurate measurement of the pulp mat, an endless apron 21, supported on a plurality of rolls 22, is led over a portion of the cylinder mold in such a way as to engage the pulp mat immediately after its formation beneath the surface of the suspension and to pass between the pulp mat and the movable measuring roll 23 which is adapted to move in a vertical direction in response to variations in the thickness of the pulp mat, being guided by links 24 which may be mounted in such a way as to counterbalance most of the weight of the roll 23, so that a light uniform pressure is maintained on the apron and the pulp mat beneath it, the pressure being reproducible for succeeding runs of pulp when the operation of the tester is intermittent. The cylinder 11 and preferably one or more of the rolls 22 may be operatively connected with the power source 20, or may be driven at a substantially constant speed by any other desired means. When a constant speed is maintained, the measurement of the thickness of the mat is also a measure of the rate of removal of pulp from the suspension. The apron 21 is preferably made of a strip of thin, transparent, practically incompressible material, such as celluloid, and serves to compress the pulp mat evenly, to prevent wrinkling of the mat, to prevent the measuring roll 23 from sinking into the soft mat and thus engaging it with varying pressure, and to prevent the mat or portions of it from adhering to the measuring roll. The incompressibility of the apron is necessary for precision in measuring the thickness of the mat, while its transparency permits observation of the mat. The presence of pulp on the apron between it and the roll 23 which would add a false thickness to the mat is prevented as by suitable jets of water directed against the upper surface of the apron as it emerges from the suspension in the vat by nozzles 25 connected to a supply pipe 26.

The movement of the roll 23 through the intermediacy of a hunting mechanism generally indicated as 27 controls a mechanism,

hereinafter described, for automatically indicating the thickness of the mat. A suitable hunting mechanism is illustrated in detail in Figure 12. As shown in Figure 10, a flexible element 28 is connected with the roller 23 so as to rise and fall therewith. Its upper end, as shown in Figure 12, is secured to an end of a short cross-piece 29 which is also supported by a flexible member 30 positioned parallel to the member 28 and fixed to an arm 31 on a nut 32. This nut is threaded on a screw shaft 33 which is supported for rotation by bearings 34 and 35 in the frame 36. The nut 32 is constrained from rotation so as to travel on the shaft 33 as the latter turns. Extending upwardly from the cross-piece 29 and fixed thereto is a fork 37, the tines of which straddle a pin 38 fixed on a block 39 pivotally hung from a bracket 40. This bracket also supports spring contacts 41, 42 and 43, so arranged that motion of the fork 37 will swing the block 39 against either one of the contacts 42, pressing it against the adjacent contacts 41 or 43 and closing a circuit to operate a motor 44. It will readily be seen that by making the cross-piece 29 relatively short and the fork 37 relatively long, any slight longitudinal motion of the flexible member 28, such as would be occasioned by a change in the thickness of the pulp mat, will result in a greatly magnified motion of the tines of the fork 37 so that the circuit-closing device described above may be made very sensitive to slight motions of the flexible member 28. When the equilibrium of the system is upset by a change in mat thickness, so as to start the operation of the motor 44 in one direction or the other, the motor turns the shaft 45, which through a worm 46 and gear 47 turns the screw shaft 33, causing the nut 32 to travel up or down a distance equal to the displacement of the member 28. This follow-up movement of the nut 32 levels the cross-piece 29, and returns the fork 37 to its normal position, thus breaking the electrical circuit, and stopping the motor 44. As will hereinafter be described, the motor 44 also operates indicating mechanism which is thus responsive to the thickness of the pulp mat.

The pulp mat after passing under the roll 23 and being measured is cut up as by jets from suitable nozzles 48 and removed from the Fourdrinier screen as by jets directed against the inner surface of the screen from within the cylinder, the pump being caught as by a doctor 49 and carried off through a drain 50. During the formation of the pulp mat on the lower portion of the Fourdrinier screen, a constant reduced pressure is maintained within the cylinder mold by any suitable means, so that the suspending liquid is drawn through the mat and the screen, and flows out through pipe 51 into a

flow meter, which includes a receptacle indicated at 52 and which will be described later.

I will now describe a preferred construction of the cylinder mold 11 with connected apparatus for maintaining a constant hydrostatic head on the pulp mat during its period of formation on the Fourdrinier screen. This construction is illustrated in Figures 10 and 11 wherein the cylinder 11 is shown as mounted for rotation on a stationary plug 53 which is preferably tapered. The cylinder preferably consists of a bronze shell which is provided with a large number of equally spaced radially disposed longitudinal slots which widen or diverge outwardly to form knife edges at the periphery of the roll about which a screen or strip of Fourdrinier wire is tightly wound. Preferably the screen or wire is formed in a narrow strip which is wound helically about the cylinder, the edge of successive convolutions of the strip abutting together so as to present no protuberance on the periphery of the mold. The tapered ends of the strip are soldered to the unslotted end portions of the shell, the soldered parts being overlapped and covered by a pair of rubber deckles 54, one of which abuts against a peripheral flange 55 of the shell. The other deckle abuts against a removable collar 56 which is secured to the end of the shell opposite to that on which the flange 55 is formed. Removal of the collar 56 permits the removal or replacement of the deckles 54. Any suitable mechanism may be provided for rotating the cylinder at constant speed. For example, a worm gear 57 may be secured to one end engaging a worm 58 on a shaft 59 which may be connected in any preferred manner to a suitable source of power. The worm and gear are preferably enclosed in a suitable housing 60 mounted on fixed supports (not shown).

The shell of the cylinder and the plug 53 have a ground and lapped fit so as to form an air-tight and water-tight joint. Provision is made for adjusting the plug axially relatively to the shell to compensate for wear and to maintain the water-tight joint between them. To this end, there are placed upon threaded portions of hub members 61, 62 of the plug clamp nuts 63, 64, which bear against the ends of the shell. By rotating these nuts in one direction or the other, the plug may be adjusted lengthwise of the shell. Each clamp nut is split, and its sections may be drawn together by bolts 65, 66, thereby tightly clamping the nuts on the hubs 61, 62. The plug is supported by its hubs on standards 67, 68, which are fixed to suitable framework (not shown), and is held against rotation by cap clamps 69, 70. The hubs 61 and 62 of the plug are hollow, the interior of the hub 61 communi-

cating with a chamber 71 within the cylinder by a port 72, and the interior of the hub 62 communicating with a chamber 73 within the cylinder mold by a port 74. The chambers 71, 73 are formed between the shell 70 of the cylinder and the plug by recesses in the plug. The level of the pulp suspension in the vat being kept at the axis of the cylinder mold and of the plug, the latter is so arranged that the chamber 71 is above the 75 level of the stock suspension while the chamber 73 is below it. Suction is maintained in both these chambers as the cylinder is being rotated so that the water component of the stock suspension which passes through the mat of pulp formed and being formed on the submerged portion of the Fourdrinier screen 12 and through the slots in the shell of the cylinder mold flows outwardly through the hub 62 and down the vertical 80 conduit 51 to the water-meter tank 52. It is desirable that suction be maintained in the chamber 71 for several reasons; first, to prevent any possibility of leakage of air from this chamber past the joint between the shell 90 of the cylinder mold and the plug into the chamber 73; second, to hold the mat of pulp on the screen as the latter rises above the level of the suspensions in the vat; third, to prevent the mat from being picked up by 95 the apron 21 after engagement with the latter during a portion of its travel on the cylinder mold. Means are provided for maintaining a balance between the suctions in the chambers 71 and 73. The hollow hub 100 62 connects with the vertical conduit 51, part of the connection being a glass tube 75 for purposes of observation. The hollow hub 61 opens into a discharge conduit 76 which extends vertically downward and is 105 slightly longer than the conduit 51, its lower end extending beneath the surface of water in a suitable receptacle not shown, whereby under a vacuum sufficient to keep the siphon comprising the hollow hub 62, the chamber 110 73 and the conduit 51 full of water, the water will not rise in the conduit 76 sufficiently to interfere with the draining of the chamber 71 through the hollow hub 61. A balanced suction is maintained in the 115 chambers 71 and 73 through a pipe 77 which is connected to both the conduits 51 and 76 by pipes 78 and 79. A constant suction is maintained in the pipe 77 by any suitable means. For example, a suitable aspirator 120 80 may be connected as by a pipe 81 to a standpipe 82 extending upwardly into the closed tank 83. The end of the pipe 77 also extends into the tank 83. Air is drawn from the tank 83 by the aspirator creating a 125 suction which is communicated to the hubs 61 and 62 and the chambers 71 and 73 by the pipes 78 and 79. This suction may be maintained substantially constant by supplying air to the tank 83 as needed to prevent an 130

excess of suction. The admission of air may be regulated by mercury seal 84 in a closed tank 85 with which the pipe 82 communicates. An air inlet pipe 86 extends below the surface of the mercury to a depth corresponding to the suction desired in the tank 83, as will be readily understood from the drawing. Any water which may be drawn into the tank 83 will be carried off by 10 a drain pipe 87 which leads from the bottom of the tank downwardly into a suitable water trap. It is obvious that with the construction described above, the aspirator 80 will be capable of maintaining a constant balanced suction in the chambers 71 and 73, the chamber 73 and the siphon associated with it being kept full of water and the chamber 71 drained, and will thus provide for a constant hydraulic head on the white water 20 flowing through the pulp mat, which is highly desirable in making measurements of freeness or slowness.

For removing the pulp mat from the screen 12 after it has passed under the measuring roll 23, a supply of water is led in through a pipe which may, as shown, enter the hollow interior of the hub 61 and extend coaxially therewith to a central recess 88 in the plug 53. Suitable passages lead radially outward from the recess 88 from which the water emerges in jets 89 through the longitudinal slots and the Fourdrinier screen, completely washing the pulp from the passing surface of the latter.

With certain types of flow meters, such as the one which will be hereinafter described, it is important that the temperature of the liquid passing through the pulp mat be maintained substantially constant. This is because the viscosity of liquids, such as water, varies sharply with the temperature, and the rate of flow of a liquid through the capillary pores of the mat is very sensitive to changes in its viscosity, whereas in a flow meter having a single relatively large exhaust port by passage through which the flow is measured, the effect of variation in the viscosity of the fluid is relatively small. To maintain the contents of the vat at a constant temperature, steam may be supplied through a perforated pipe 90 and valve 91 which is controlled through a diaphragm motor 92 by a thermo-responsive element 93. The pulp suspension may, if preferred, be warmed by heating coils, but the direct introduction of steam into the mixture has been found satisfactory. It is preferred to maintain the suspension at a temperature slightly higher than the maximum temperature of the river water used in the mill, so that by more or less heating as conditions may require a constant temperature may be effected. A suitable flow meter for measuring the rate of outflow of the white water after it has passed through

the pulp mat is clearly shown in Figure 3. The white water entering the receptacle or tank 52 through pipe 51 passes baffle plates 94 and 95 and drains out through an opening 96 in the form of a semicircular slot, 70 which is accurately cut in a plate 97 set into the bottom of receptacle 52 and is carried off by drain pipe 98. The baffle 95 with a partition 99 constitute a water seal and prevent air working back to the pipe 51. 75

The rate of flow of white water is measured by the amount of opening of the slot 96, through which the white water passes out from the tank 52, necessary to balance the inflow through the pulp mat and the pipe 51 and maintain a constant level in the tank 52. This level is maintained at normal by automatic mechanism including a float 100 which controls a motor 101 operating a shutter 102 to increase or diminish the amount of opening of the slot 96. The float 100 is located in a compartment of the receptacle 52 formed by the partition 99 and a perforated portion of the baffle 95. The float controls the motor 101 through a flexible member 103 which connects it with an arm of a lever 104 shown in Figure 1 in the form of a T, mounted on a knife-edge support 105. On the opposite side of the support, a weight 106 is provided to counter-balance the float 100 and the flexible member 103. The long arm 107 of the lever carries an electric contact point 108 which contacts with point 109 or 110 to close a circuit to operate the motor 101 in one direction or the other according as the float 100 rises or falls. The point 108 is insulated from the lever 104 by a cap 111 of fiber or any desired insulating material. A fine insulated wire 112 is led from the point 108 along the arm 107 and leaves it through a spring coil 113 near the support 105 to connect point 108 with the motor 101 and a source of electrical energy. The motor 101 is operatively connected by suitable shafts and gearing both 110 to the shutter 102 and to a threaded shaft or rod 114 on which a nut 115 is held against rotation so as to travel longitudinally of the shaft 114 when the latter is rotated. The motion of the nut 115 is thus concurrent 115 with the motion of the shutter 102 and its position on the shaft 114 is a measure of the amount of opening of the slot 96, hence of the rate of outflow of the white water.

The mechanical connection of the motor 101 with the shaft 114 is effected through a suitable reduction gearing 116, shaft 117 and bevel gears 118 and 119, the latter being fixed to the shaft 114. To connect the motor further with the shutter 102, a gear 120 is mounted on the shaft 114 meshing with a gear 121 mounted on a shaft 122 which turns a shaft 123 through a worm and gear 124. The shaft 123 through a worm and gear 125 turns the shaft 126 on which the 120

shutter 102 is fixed. The slot 96 is cut in a plate 97 which is fitted in the bottom of the flow-meter receptacle 52 and on the upper surface of which the shutter 102 slides. The shaft 126 extends through the plate 97 and a light spring 127 on its protruding end serves to keep the shutter 102 snugly against the face of the plate 97. The slot 96 is preferably cut with a trapezoidal cross section, the narrower portion being uppermost so that the water in passing out touches only the upper edges. It has been shown experimentally that the rate of flow of water through a slot of that kind with uniform width is directly proportional to the angular amount of opening where the slot is in the shape of a circular arc. The motion of the nut 115 on the shaft 114 being proportional to the motion of the shutter 102 is also proportional to angular amount of opening of the slot 96,—hence the position of the nut 115 is a measure of the rate of flow of the white water from the cylinder 11. If desired, this rate of flow can be directly indicated on a scale 128 by mounting an index 129 on the nut 115 and fixing the scale in a convenient position behind the index and parallel to the shaft 114.

The mechanism for indicating the thickness of the pulp mat formed on the cylinder 11 will now be described. As previously stated, vertical movement of the roll 23 produced by variations in the thickness of the pulp mat operates a hunting mechanism which controls the rotation of the motor 44. This motor through a suitable set of reduction gears, generally indicated at 130, drives a threaded shaft or rod 131 supported at right angles to the shaft 114 in bearings 132 and 133, a reduced end 134 of which shaft is geared to the shaft 45 which is connected with follow-up mechanism (described above) for restoring the hunting device to its normal position, after it has been displaced by a variation in the thickness of the pulp mat to start operation of the motor 44 in one direction or the other. Mounted parallel to shaft 131 and geared thereto by equal gears 135 and 136 is a similar threaded shaft 137. As shown in Figure 5, shafts 131 and 137 support a carriage 138 threaded thereon to move longitudinally thereof when the shafts 131 and 137 are rotated. The shaft 137, if preferred, may be made smooth for sliding engagement with the carriage 138, dispensing with the gears 135 and 136. Since a displacement of the hunting element in the hunting mechanism by a vertical movement of the roller 23 responsive to a change in the thickness of the pulp mat requires rotation of the motor 44 to restore the hunting element to normal position, and since the rotation of the motor 44 at the same time moves the carriage 138 along the shaft 131, the position of the carriage 138 on the shaft 131 is thus

a measure of the thickness of the pulp mat. It is evident that a pointer 139 on the carriage 138 and a scale 140 fixed parallel to shaft 131 can be used to indicate the thickness of the mat in any desired units.

To provide a scale and means for automatically indicating thereon the product of rate of flow of white water by the thickness of the pulp mat as a measure of the free-ness of the pulp, two parallel slotted plates 141 and 142 are secured to the carriage 138 and depend vertically therefrom. Fixed to the carriage 138 in front of these plates is a plate 143 graduated with suitable scale markings. A rider 144 is mounted to slide lengthwise of the graduated plate and is provided with oppositely disposed pointers 145 to indicate the position of the rider relative to the scale on the graduated plate. The rider 144, as shown, comprises a member 146, preferably of metal, which has a central boss 147 to project through the slots in the plates 141 and 142. A ring or roller 148 is mounted on the boss to ride between the plates 141 and 142. The rider is retained in slidable relation with the plates 141, 142 and 143 by a pair of nuts 149 and 150 on the threaded outer end of the boss. On the front face of the member 146 are fixed blocks 151 of insulating material, such as fiber, the pointers 145 also being preferably of the same material. These blocks support spring contacts 152 and 153 which have a sliding contact with wires 154 and 155 respectively, and are electrically connected by a wire 156, which wires are a part of a recording system and will be referred to hereinafter in the description of the wiring diagram of Figure 13.

Motion of the rider 144 along the scale may be caused by a slotted lever or link member 157 which is pivoted to the bracket 132 at A. Riding in the slot of this link member is the boss 147 of the rider 144, the roller 148 engaging the sides of the slot in the link member 157 and fitting closely therein. The slot of the link member 157 also engages closely a pin 158 on the traveler 115, so that motion of the traveler 115 along the shaft 114 will swing the link member 157 on its pivot A, and will thus determine the angle which the link 157 makes with the shaft 131 at A. The motion of the lever 157 also may impart motion to the rider 144 up or down the scale of the plate 143. When the shafts 131 and 137 are rotated, the carriage 138 is constrained to travel lengthwise thereof and in a direction transverse to the plate 143. The carriage 138 in its motion carries with it the plates 141 and 142 which also may impart motion to the rider 144 up or down the scale, the amount of such motion of the rider 144 corresponding to a given motion of the plates 141 and 142 depending on the angular relation between the link 157 and the shaft 131. It is

thus obvious that the rider 144 is responsive to motion of both the carriage 138, which measures the mat thickness, and the traveler 115, which measures the outflow of white water. That the position of the rider 144 on the scale member 143 may be an indication of the product of the mat thickness by the outflow of the white water is shown by reference to the properties of similar triangles which in this case are defined by the projection onto a common plane of the axes of the shafts 114 and 131, and of the center lines of the link member 157 and the scale plate 143, as on the plane of the paper in Figure 1 of the drawing. These projected lines intersect at points A, B, C, D and E, the point A also being in the pivot axis of the link member 157, the point C being the projection of the center of the pin 158, and the point E being the projection of the center of the boss 147 of the rider 144. As will be seen from Figure 1, ABC and ADIE are similar right triangles, and by the well known rule of proportionality of corresponding sides of similar triangles,

$$AB:BC = AD:DE, \text{ or } DE = \frac{AD \times BC}{AB}.$$

Since AB here is a constant quantity, it is seen at once that DE is proportional to the product of AD and BC. Since in the mechanism shown, AD is a measure of thickness of the pulp mat and BC is a measure of the rate of outflow of white water, DE will be a measure of the product of these two quantities, hence of the freeness of the pulp. The scale may be calibrated with any convenient units desired, and when it is used to indicate freeness of the pulp, the markings will be equally spaced. It is obvious that it may also be calibrated to read in terms of the slowness of the pulp, in which case the spacing between successive graduations of the scale will increase as they descend, since the slowness is not directly but inversely proportional to the product of the thickness of mat by the flow of white water. If desired, two scales may be marked on the plate, one reading in terms of freeness, the other in terms of slowness.

It is also obvious that if the outflow of white water be kept constant, the length of DE, determined by the position of the rider 144 on the scale member 143, will be a measure of the thickness of the pulp mat as well as of the freeness of the pulp and the scale 143 can be calibrated accordingly to read in terms of mat thickness for any given rate of outflow. Likewise, if the mat thickness be kept constant, the length of DE will be a measure of the rate of outflow as well as of the freeness of the pulp, and the scale can be calibrated accordingly to read in terms of outflow for any given thickness of the mat.

Figure 6 shows a means for preventing

endwise play in the shafts 114, 131 and 137. Each of these shafts at one end has a reduced portion 159 on which is rotatably mounted an externally threaded sleeve 160 which is threaded through an aperture in the member supporting that end of the shaft. The sleeve 160 is provided with a knurled head 161 by which it is turned and thus set up against a shoulder 162 on the shaft, holding the shaft against lengthwise motion. A nut 163 is used to lock the sleeve 160 in adjusted position.

To avoid damage to the apparatus in case any part fails to function properly, limit stops are provided to shut off the current from motors 101 or 44 when the traveler 115 or the carriage 138 has reached a limiting position at either end of the shaft on which it travels. These limit stops are preferably in the form of electric switches 164, 165, 166 and 167. On the traveler 138 are mounted two members 168 and 169 which engage switches 164 and 165, respectively, when the traveler 138 reaches its corresponding limiting position and breaks the circuit connecting the motor 44 with its source of power, as may be seen from the wiring diagram in Figure 13. In like manner, members 170 and 171 are mounted on the traveler 115 to open switches 166 or 167 respectively, when the traveler 115 reaches its corresponding limiting position, breaking the circuit connecting the motor 101 with its source of power.

I will now describe my improved mechanism for automatically controlling the admission of pulp into the vat so as to maintain a pulp suspension in the vat of substantially constant consistency, that is, to maintain a substantially constant ratio of solid matter to the liquid of the suspension in the vat. As has been previously stated, the ratio of the thickness of the pulp mat to the rate of flow of the white water varies closely with the concentration of pulp in the suspension. It will be seen therefore that the pulp suspension may be kept substantially constant by employing means which tend to decrease the rate of admission of pulp into the vat when the thickness of the pulp mat increases, and to increase the inflow of pulp as the rate of flow of white water increases, and vice versa.

The shafts 114 and 131, which are responsive to changes in the flow of white water and mat thickness, respectively, are utilized to control the admission of pulp into the vat as follows. The pulp is admitted from the sampling box 4 through the gate valve 6 which is controlled through a diaphragm motor 172 by the relay valve indicated as 173. The mechanism for operating the relay valve 173 is shown in Figure 4, some of this mechanism being omitted from Figure 1 to prevent confusion of detail. Referring to

Figures 1 and 4, it will be recalled that a change of thickness in the pulp mat results in the rotation of shaft 131. This shaft is geared to a vertical shaft 174 by bevel gears 175 and 176. Fixed to the shaft 174 is a gear 177 which meshes with a gear 178. A vertical shaft 179 has a reduced portion 180 sliding in a bearing in a bracket 181. The lower portion of shaft 179 is threaded and 10 has a slot 182 extending lengthwise thereof (Figure 9). This shaft passes through the brackets 183 and 184, gear 178 and gear 185. The gears 178 and 185 are spaced from the brackets 183 and 184 and from each other by 15 suitable collars 186 loosely surrounding the shaft 179.

It will also be recalled that a variation in the flow of white water will result in a rotation of the shafts 114 and 122. Fixed to 20 the shaft 122 is a gear 187 meshing with the gear 185. Hence a variation in the thickness of the pulp mat will cause a rotation of the gear 178, while a variation in the flow of white water will cause a rotation of the 25 gear 185. The gear 178 is bored out and a bushing 188 is fixed therein which fits snugly about the shaft 179 and has a lug formed integrally fitting into the slot or groove 182 in the side of the shaft 179 so that the shaft 30 179 is free to slide lengthwise with respect to the gear 178, but is constrained to turn with that gear. The gear 185 is threaded on the shaft 179. As will be seen from Figure 35 9, rotation of the gear 185 will result in longitudinal motion of the shaft 179 provided the shaft is restrained from rotation. Likewise if the gear 185 is held fixed and the gear 178 is rotated, the shaft 179 turning with the gear 178 will move longitudinally 40 by reason of its threaded engagement with the gear 185. Since the gears 178 and 185 are responsive to variations in the thickness of the pulp mat and the flow of white water respectively, it is clear that any such variation 45 will result in longitudinal motion of the shaft 179, and hence in an operation of the relay valve 173, which is connected thereto, unless the variations in thickness of the pulp mat and in the flow of white water are such 50 as to maintain the desired ratio of the one to the other. In this event, the rotations of gear 178 and of gear 185 offset each other so far as the longitudinal motion of the rod 179 is concerned. In order to limit the effective 55 range of motion of the shaft 179 and thus to stabilize the action of the valve 6, the shaft 179 is not directly connected to the relay valve 173, but operates it through a mechanism shown in Figures 4 and 7. This mechanism may comprise a member or tooth 189 adjustably secured to the shaft 179 by nuts 190, which engages in a recess between two teeth 191 and 192 on a yoke 193 pivotally mounted as at 194 on a bracket 195. 60 Between the arms 196 of the yoke is pivotally connected a rod 197 which operates the relay valve 173 and thereby regulates the inflow of pulp through the gate valve 6. It will be apparent that no matter how far up or down the shaft 179 may be moved under the influence of changes in mat thickness or white water flow, or both, the variation in the opening of the gate 6 and hence in the rate of admission of pulp to the container 1, will be limited by the narrow range 70 of motion of the yoke 193 from its neutral position. The mechanism controlling the opening of the gate 6 thus avoids wide fluctuations and serves to maintain a balanced condition of stock concentration in the tester 75 when it is at or near its normal state of equilibrium. The relay valve may be of any preferred type. As shown in Figure 4, it comprises a ball valve 198 which when seated 80 closes the inlet pipe 199 which carries air, water, or other fluid, as preferred under a substantially constant pressure, which may be supplied from any convenient source. The valve stem 200 is adjustably connected to the rod 197 as by a rod 197^a screw-threaded or otherwise suitably secured to the rod 197. 85 A resilient connection is preferably interposed between the rod 197^a and the valve stem 200 by means of which the ball valve 198 may be held resiliently on its seat against 90 the pressure of the fluid in the inlet pipe 199 when the rod 197, 197^a is near its lower limit. The connection as shown comprises a pair of rods 300 extending downwardly 95 from the end of a cross piece 301 fixed to the lower end of the rod 197^a. The rods 300 extend through holes in the ends of a cross piece 302 which is secured to the upper end of the valve stem 200. Springs 303 around the rods 300 are compressed between the 100 cross bars 301 and 302. Nuts 304 on the ends of the rods 300 limit the action of the springs and the separation of the cross pieces. The valve stem 200 enters the valve chamber through an aperture 201 large 110 enough to permit the escape of fluid from the valve chamber around the stem. A pipe 202 leads from the valve 173 to the diaphragm motor 172. The operation of the valve is as follows: The rod 197, 197^a is preferably 115 adjusted so that when the yoke 193 is in its "neutral" position, as in Figure 4, the compression of the springs 303 is light enough to permit some of the fluid under pressure in the inlet 199 to push the ball 120 valve 198 slightly upward and escape into the valve chamber, raising the pressure in the pipe 202 to an intermediate value less than maximum. This pressure in the pipe 202 actuates the diaphragm valve 172 to 125 open the gate 6 until the pressure on the diaphragm is balanced by the increasing tension of a spring 172^a or other suitable opposing force. It is desirable to adjust the length of the rod 197, 197^a, so that the gate 130

ally connected a rod 197 which operates the relay valve 173 and thereby regulates the inflow of pulp through the gate valve 6. It will be apparent that no matter how far up or down the shaft 179 may be moved under the influence of changes in mat thickness or white water flow, or both, the variation in the opening of the gate 6 and hence in the rate of admission of pulp to the container 1, will be limited by the narrow range 70 of motion of the yoke 193 from its neutral position. The mechanism controlling the opening of the gate 6 thus avoids wide fluctuations and serves to maintain a balanced condition of stock concentration in the tester 75 when it is at or near its normal state of equilibrium. The relay valve may be of any preferred type. As shown in Figure 4, it comprises a ball valve 198 which when seated 80 closes the inlet pipe 199 which carries air, water, or other fluid, as preferred under a substantially constant pressure, which may be supplied from any convenient source. The valve stem 200 is adjustably connected to the rod 197 as by a rod 197^a screw-threaded or otherwise suitably secured to the rod 197. 85 A resilient connection is preferably interposed between the rod 197^a and the valve stem 200 by means of which the ball valve 198 may be held resiliently on its seat against 90 the pressure of the fluid in the inlet pipe 199 when the rod 197, 197^a is near its lower limit. The connection as shown comprises a pair of rods 300 extending downwardly 95 from the end of a cross piece 301 fixed to the lower end of the rod 197^a. The rods 300 extend through holes in the ends of a cross piece 302 which is secured to the upper end of the valve stem 200. Springs 303 around the rods 300 are compressed between the 100 cross bars 301 and 302. Nuts 304 on the ends of the rods 300 limit the action of the springs and the separation of the cross pieces. The valve stem 200 enters the valve chamber through an aperture 201 large 110 enough to permit the escape of fluid from the valve chamber around the stem. A pipe 202 leads from the valve 173 to the diaphragm motor 172. The operation of the valve is as follows: The rod 197, 197^a is preferably 115 adjusted so that when the yoke 193 is in its "neutral" position, as in Figure 4, the compression of the springs 303 is light enough to permit some of the fluid under pressure in the inlet 199 to push the ball 120 valve 198 slightly upward and escape into the valve chamber, raising the pressure in the pipe 202 to an intermediate value less than maximum. This pressure in the pipe 202 actuates the diaphragm valve 172 to 125 open the gate 6 until the pressure on the diaphragm is balanced by the increasing tension of a spring 172^a or other suitable opposing force. It is desirable to adjust the length of the rod 197, 197^a, so that the gate 130

6 will be held open by the balance of the diaphragm 172 against the spring 172^a at such a point as will admit pulp into the vat at substantially the same rate at which it is being removed therefrom. This arrangement of parts avoids "see-sawing" of the gate 6 and insures a substantially constant rate of supply during the normal operation of the device. Whenever there is a change in the flow of white water or in the thickness of the pulp mat, unless these changes balance each other, there will be a movement of the shaft 179 tilting the yoke 193 and raising or lowering the rod 197, 197^a. This results in an increase or diminution of the compression of the springs 303 permitting less or more of the compressed fluid to push past the ball valve 198, and thus varying the fluid pressure against the diaphragm of the motor 172, which will alter the position of the gate 6 until again balanced by the tension of the spring 172^a. The compressed fluid entering the valve chamber passes out through the slight clearance of the aperture 201 about the valve stem 200. This permits a pressure in the chamber which is intermediate of atmospheric and that in the inlet and is regulated by the rate at which the fluid is permitted to escape past the ball valve. The use of fluid pressure in controlling the position of the gate 6 makes it possible to locate the tester at any desired distance from the sampling box.

Should the variation in position of the shaft 179 be excessive owing to some abnormal conditions, the member 189 will travel clear of the teeth 191 and 192. In order to make certain that the teeth will be in position to reengage the member 189 when it returns to its normal range of motion, the yoke 193 is provided with beveled edges 203 against one of which a plug 204 is adapted to press when the member 189 moves out of range of the teeth. This holds the teeth in proper position for reengagement by the member 189. The plug 204 is fitted into a bore in the bracket 195 and is pressed outwardly by a spring 205 which abuts a screw-threaded plug 206.

Referring to the wiring diagram shown in Figure 13, contact points 41, 42 and 43, with their spark-absorbing shunts 207 and 208, are a part of the hunting mechanism previously referred to which controls the rotation of the motor 44, the armature and field windings of which are indicated at 209 and 210, respectively. 211 and 212 represent high resistance coils which are necessary in operating the motor 44 in opposite directions.

The contact points 109, 108 and 110, with their spark-absorbing shunts 213 and 214, likewise control the operation of the motor 101, the armature and field windings of which are indicated at 215 and 216. The

high resistance coils for use in operating the motor in opposite directions are shown at 217 and 218. The motors 101 and 44 are indicated by the diagram as being series wound. A suitable source of electric energy is indicated at 219. The motor 44, as previously mentioned, is in series with the limit stop switches 164 and 165. The motor 101 is likewise in series with the limit stop switches 166 and 167.

The readings of the scale on plate 143 may be automatically reproduced at any desired distance by the circuits now to be described. 156 represents the wire carried by the rider 144 which, with the spring contacts 152 and 153, provides an electrical connection between the wires 154 and 155 carried with the plate 143 by the carriage 138. The wire 154 is a resistance wire of uniform cross section and is connected at its ends electrically through coil springs 220 and 221 to a battery 222. The wire 155 is connected to a metal piece 223 and coil spring 224 to a lead 225 running to a recording potentiometer indicated generally as 226. The springs 220 and 221 permit the travel of carriage 138 along shafts 131 and 137 with the assembly of parts supported thereby, expanding or contracting in conformity to this travel.

With the battery 222 is provided a resistance 227 with a sliding contact 228 by which the voltage in the recording circuit may be regulated as desired. From an inspection of this circuit, it can be seen that the potential difference in the recording circuit will be proportional to the length of the wire 154 included between point 229, which is opposite the zero point of the scale on the plate 143, and point 230 which is equivalent to the position of the pointers 145. The recording potentiometer 226 is of a well-known type constructed to balance automatically the potential on wire 154 by a contact sliding on a fine uniform wire 231. The sliding contact 232 automatically records its motion on a chart 233, which may be graduated to read in terms of freeness or of slowness of the pulp, as desired. A recording system of this type is not affected by the length of the leads connecting the recording potentiometer with the varying source of potential, nor is it affected by the uncertain contact resistances of sliding spring contacts, since there is no current flowing past such contact points when the system is in equilibrium.

In Figure 14, I have shown diagrammatically a wiring plan which is designed to provide a more delicate and reliable link between the "hunting" device actuated by changes in the pulp mat thickness and the motor 44^a. In the practical operation of the slowness tester, it has been found that it was necessary for the contact 42 to press against the contact 41 or 43 with substantial force in order to allow sufficient current to flow

to actuate the motor 44. Since the ratio of motion of the end of the fork 37 to that of the measuring roll 22 is approximately 500 to 1, it is evident that the necessary pressing force of the contact 42 must be kept as small as possible since the magnified force on the supporting members 28, 29, and 30, would unduly distort these delicate parts. It is also necessary to avoid any possibility of the contacts sticking as the force available to separate them is necessarily very small. The wiring system obviates these difficulties by means of a relay circuit which operates with a very light touch of the contact points and a very small current. The diagram in Figure 14 and the description which follows are given by way of illustration only and may be varied as may be required. In the improved relay circuit, the contact points of the "hunting" device illustrated in Figure 12, are indicated at 41^a, 42^a, 43^a. The contact point 42^a, which may be moved by the fork 37 into contact with points 41^a or 43^a, is connected to the grid 400 of a triode tube (as for example, radiotron U V 201 A), the plate 401 of which is connected to the positive terminal of a 110 volt D. C. supply through a high resistance relay coil 402. This relay operates to bring the point 42^b into contact with 41^b or 43^b according as the point 42^a touches 41^a or 43^a, the potentials of the latter points being such that when 41^a is touched, a moderate plate current from the filament 403 flows through and closes the relay 402 against a suitable restoring force, such for example, as a light spring 409, thereby drawing the point 42^b into contact with the point 41^b, closing the circuit through the armature 209^a of the motor 44^a and one branch of the field winding 210^a, and causing the motor to rotate in a direction to operate the follow-up mechanism in the hunting device and restore the fork 37 to its normal position. When the point 43^a is touched, a very slight plate current flows, permitting the relay to open and the point 42^b to be moved into contact with the point 43^b, causing the motor 44^a to rotate in the opposite direction. If, for example, a 50-ohm resistance unit be used at 405, a 200-ohm unit at 406, and a 375-ohm unit at 407, the resistance of the relay coil being 20,000 ohms, the sliding contact on the resistance unit 406 may be adjusted to give a filament voltage of 3.5 volts and a potential difference between the filament and plate of 50 to 100 volts. It has been found that such a combination utilizes to best advantage the characteristics of a triode tube. Contact of the point 42^a with the point 41^a will put a potential of about 0 volts on the grid, giving a plate current of the order of one or two milliamperes which is amply sufficient to close the relay. Contact with the point 43^a will put a potential of about

-12 volts on the grid, giving a plate current too small to keep the relay closed. In neither case does the grid current (which passes through the micrometer contacts 41^a, 42^a, 43^a) exceed 0.03 microamperes. Because of leakage and of electron currents in the triode, the grid potential does not in general remain constant while the point 42^a is moving between 41^a and 43^a, but drifts towards some particular value. A 0.01 microfarad condenser is inserted at 408 to increase the electrostatic capacity of the grid, so that the potential drifts more slowly. A resistance of 10,000 ohms inserted at 404 prevents the condenser charging current from sparking at the contacts. The condenser also serves to prevent the possibility of chattering at the contacts being passed on to the relay. It is evident that since the resistance of the filament-grid circuit is very high, the pressure of the contacts necessary to close the circuit will be correspondingly minute, and that since the current flowing through the closed contact is exceedingly low, the tendency to stick will be negligible.

It is to be understood that wherever the terms "freeness" or "slowness" are used in the claims, either term may be replaced by the other, inasmuch as they bear a simple reciprocal relation one to the other, and that where apparatus for measuring one is claimed, it is intended to include apparatus for measuring the other.

The disclosure of the invention in the drawings and description is not intended as limiting the invention in any way, but merely as setting forth a preferred embodiment thereof.

What I claim is:

1. In a device of the class described, a container for a pulp suspension, means for forming a mat of the pulp of the suspension, means for causing the liquid of the suspension to flow through the mat, means for subjecting the mat to a uniform and reproducible compression, and means for indicating variations in the thickness of the mat, said indicating means including a rectilinear scale and a pointer movable relatively thereto.

2. In a device of the class described, a container for a liquid suspension of pulp, means for forming a mat of the pulp of the suspension, means for causing the liquid of the suspension to flow through the mat, and means for automatically indicating variations in the flow of the liquid through the mat, said indicating means including a rectilinear scale and a pointer movable relatively thereto.

3. In a device of the class described, a container for a liquid suspension of solid matter, means for forming a mat of the solid matter, means for causing the liquid of the suspension to flow through said mat, and

- means for indicating the product of the thickness of the mat by the flow of the liquid, said indicating means including a rectilinear scale and a pointer movable relatively thereto. 5
4. In a device for determining the freeness of an aqueous suspension of pulp, a container for the pulp suspension, means for forming a mat of the pulp of the suspension, 10 means for causing the liquid of the suspension to flow through the pulp mat, and means for indicating the freeness of the pulp suspension, said means including a rectilinear scale and a pointer movable relatively thereto and responsive to the variations of thickness of the pulp mat. 15
5. In a device for determining the freeness of pulp suspended in a liquid, a container for the pulp suspension, means for forming a mat of the pulp of the suspension, 20 means for causing the liquid of the suspension to flow through the mat, and means for indicating the freeness of the pulp, said indicating means including a rectilinear scale and a pointer movable relatively thereto and responsive to variations in the flow of the liquid through the mat. 25
6. In a device for determining the freeness of pulp suspended in a liquid, a container for the pulp suspension, means for forming a mat of the pulp of the suspension, 30 means for causing the liquid of the suspension to flow through said mat, and means for indicating the freeness of the pulp, said indicating means including a rectilinear scale and a pointer movable relatively thereto and simultaneously responsive to variations in the thickness of the pulp mat and the flow of the liquid passing therethrough. 35
7. In a device for determining the freeness of pulp suspended in a liquid, a container for the pulp suspension, means for forming a mat of the pulp of the suspension, 40 means for causing the liquid of the suspension to pass through the mat, and means for indicating the freeness of the pulp, said indicating means including a rectilinear scale and a pointer movable relatively to the scale and responsive to changes in the quantity of pulp forming a given area of mat. 45
8. In a device for determining the freeness of pulp in a liquid suspension, a container for the pulp suspension, means for forming a mat of the pulp of the suspension, 55 means for causing the liquid of the suspension to pass through said mat, and means for indicating the freeness of the pulp, said indicating means including a rectilinear scale and a pointer movable relatively thereto and simultaneously responsive to variations in the quantity of pulp forming a given area of the mat, and to variations in the flow of liquid through the mat. 60
9. In a device of the class described, a container for a liquid suspension of pulp, means 65 for forming a mat of the pulp of the suspension, means for causing the liquid of the suspension to pass through said mat, means for indicating the thickness of the pulp mat, said indicating means including a rectilinear scale movable in a lateral direction, a rider slidably mounted for motion relative to said scale lengthwise thereof, means responsive to variations in thickness of the pulp mat for imparting lateral motion to the scale, and constraining means engaging the rider in a manner to move said rider lengthwise of the scale during lateral movement thereof. 70
10. The combination with a container for a liquid suspension of pulp, means for forming a mat of the pulp of the suspension, and means for causing the liquid of the suspension to pass through the mat, of means for indicating the flow of the liquid through the mat, said indicating means including a rectilinear scale, a rider slidably mounted for movement relative to said scale lengthwise thereof, a member movable in a direction parallel to the scale and responsive to variations in the flow of liquid through the mat, and means operatively connecting said rider with said member. 80
11. In a device for determining the characteristics of solid matter suspended in a liquid, a container for the suspension, means for forming the solid matter into a mat, means for causing the liquid of the suspension to pass through said mat, and means for indicating the quality of the suspended material, said indicating means comprising a rectilinear scale movable laterally, means responsive to variations in the thickness of the mat for imparting lateral motion to the scale, a rider slidably mounted for movement relative to said scale lengthwise thereof, a member responsive to variations in the flow of liquid through the mat and movable in a direction parallel to the length of the scale, and a link engaging said rider and said member in a manner to render said pointer responsive simultaneously to movement of said scale and said member. 95
12. In a device for determining the freeness of a liquid suspension of pulp, means for forming a mat of the pulp of the suspension, means for causing the liquid of the suspension to pass through said mat, and means for indicating the freeness of the pulp, said indicating means comprising a rectilinear laterally movable scale, a rider slidably mounted for movement relative to said scale lengthwise thereof, a member movable in a direction parallel to the length of the scale, means engaging said rider and said member in a manner to render said rider simultaneously responsive to movement of said scale and of said member, separate mechanisms for imparting movement to said scale and to said member, one of said mechanisms 100
- 120
- 125
- 130

being responsive to variations in the thickness of the pulp mat, the other mechanism being responsive to variations in the flow of liquid through the mat.

13. In a device for determining the freeness of an aqueous suspension of pulp, a container for the pulp suspension, means for forming a mat of the pulp of the suspension, means for causing the liquid of the suspension to pass through the mat, mechanism responsive to variations in the thickness of the pulp mat, other mechanism responsive to variations in the flow of liquid through the mat, and means for indicating the freeness of the pulp, said indicating means comprising members defining similar triangles having certain of their sides variable, means actuated by the movement of one of said responsive mechanisms for varying the length of one of said triangle sides, and means for indicating the corresponding length of another said triangle side as a measure of the freeness of the pulp.
14. In a device for determining the freeness of an aqueous suspension of pulp, a container for the pulp suspension, means for forming a mat of the pulp of the suspension, means for causing the liquid of the suspension to pass through the mat, mechanism responsive to variations in the thickness of the mat, other mechanism responsive to variations in the flow of liquid through the mat, and means for indicating the freeness of the pulp, said indicating means comprising members defining two right triangles having variable legs but at all times mutually similar, means for varying the length of one triangle leg in response to movement of one of said responsive mechanisms, and means for indicating the corresponding length of another triangle leg as a measure of the freeness of the pulp.

15. In a device for determining the freeness of an aqueous suspension of pulp, a container for the pulp suspension, means for forming a mat of the pulp of the suspension, means for causing the liquid of the suspension to pass through the pulp, mechanism responsive to variations in the thickness of the pulp mat, other mechanism responsive to variations in the flow of liquid through the mat, and means for indicating the freeness of the pulp, said indicating means comprising members defining two similar right triangles having certain of their sides variable, means responsive to movement of one of said mechanisms for varying a side of one triangle, and means for indicating the corresponding length of a side of the other triangle as a measure of the freeness of the pulp.

16. In a device for determining the freeness of an aqueous suspension of pulp, a container for the pulp suspension, means for forming a mat of the pulp of the suspension,

means for causing the liquid of the suspension to pass through the mat, mechanism responsive to variations in the thickness of the pulp, other mechanism responsive to variations in the rate of flow of liquid through the mat, and means for indicating the freeness of the pulp, said indicating means comprising members defining a right triangle having variable sides, means responsive to the movement of one of said mechanisms for varying the length of one of the sides of the triangle, and means for indicating the length of another side as a measure of the freeness of the pulp.

17. In a device for determining the freeness of an aqueous suspension of pulp, a container for the pulp suspension, means for forming a mat of the pulp of the suspension, means for causing the liquid of the suspension to flow through the mat, mechanism responsive to variations in the thickness of the mat, other mechanism responsive to variations in the flow of liquid, and means for indicating the freeness of the pulp, said indicating means comprising members defining a right triangle, means for varying an acute angle of said triangle in response to movement of one of said mechanisms, means for varying the length of a leg of said triangle in response to motion of the other of said mechanisms, and means for indicating the length of the other leg of said triangle as a measure of the freeness of the pulp.

18. In a device of the class described, a container for a liquid suspension of pulp, means for maintaining the suspension at a constant level, means for continuously forming a mat of the pulp of the suspension, means for causing the liquid of the suspension to pass through the mat in the course of its formation, mechanism responsive to variations in the thickness of the formed mat, other mechanism responsive to variations in the flow of liquid through the mat, and means for indicating the product of the mat thickness by the flow of liquid as a measure of the freeness of the pulp, said indicating means comprising two rods positioned at right angles to each other and defining the legs of a right triangle, a link member pivoted to one of said rods and defining the hypotenuse of said right triangle, a traveler mounted on the other of said rods for movement lengthwise thereof and in sliding engagement with said link member, a rectilinear scale member positioned parallel to the motion of the traveler and movable laterally, a rider slidably mounted for movement relative to said scale member lengthwise thereof and in sliding engagement with the link member, means actuated by the movements of one of said mechanisms for imparting motion to the traveler, and means actuated by the move-

ments of the other said mechanisms for imparting lateral motion to the scale member.

19. A device for continuously indicating the product of two variable quantities comprising in combination, members defining a right triangle, the elements of which comprising the sides and acute angles are variable, means for causing one element of said triangle to vary in response to changes in one of the variable quantities, means for causing a second element of said triangle to vary in response to changes in the other of said variable quantities, and means for indicating the magnitude of a third element of said triangle as a measure of the product of the two variable quantities.

20. A device for continuously indicating the product of two variables comprising in combination, a rectilinear laterally movable scale member, a rider slidably mounted for motion relative to said scale member lengthwise thereof, an elongated member perpendicular to said scale member, another elongated member parallel to said scale member, a traveler mounted on said parallel member for movement lengthwise thereof, a lever pivoted to said perpendicular member and slidably engaging said rider and said traveler and defining the portion of said rider on said scale member, means for swinging the lever on its pivot in accordance with the variations of one variable, and means for imparting motion to the scale member in accordance with the variations of the other said variable.

21. In a device of the class described, a container for a liquid suspension of pulp, means for continuously and separately removing pulp and liquid from the container, means for supplying pulp and liquid to the container, and means for controlling the consistency of the suspension, said controlling means comprising means for measuring the rate of pulp removal, means for measuring the outflow of the liquid, and mechanical means mechanically connected to both said measuring means for controlling the rate of admission of pulp into the container.

22. In a device of the class described, a container for a liquid suspension of pulp, means for continuously forming a mat of the pulp of the suspension, means for causing the liquid of the suspension to flow through the mat and out of the container, means for admitting liquid to the container automatically controllable to keep the suspension in the container at a substantially constant level, means for admitting pulp into the container, and means for maintaining a substantially constant ratio of solid to liquid in the suspension, said last means comprising mechanism for measuring the thickness of the pulp mat, mechanism for measuring the outflow of liquid, and mechanical means mechanically connected to

both mechanisms for controlling the admission of pulp to the container.

23. In a device for determining the freeness of a liquid suspension of pulp, a container for the suspension, means for continuously forming a mat of the pulp of the suspension, means for causing the liquid of the suspension to pass through the mat and out of the container, means for measuring the thickness of the formed mat, means for measuring the outflow of liquid, means for regulating the supply of liquid to the container to keep the suspension at a substantially constant level, means for indicating the product of the thickness of the mat by the outflow of liquid, said indicating means including a rectilinear scale and a pointer slideable thereon and means simultaneously controlled by both said measuring means for moving the pointer relatively to the scale, and mechanism for maintaining a substantially constant ratio of solid to liquid in the suspension, said mechanism comprising a valve for regulating the admission of pulp to the container and means directly responsive to movement of both said measuring means for controlling said valve.

24. In a device of the class described, a container for a liquid suspension of pulp, means for continuously forming a mat of the pulp of the suspension, means for causing the liquid of the suspension to pass through said mat, mechanism responsive to variations in the thickness of the formed mat, other mechanism responsive to variations in the flow of the liquid through the mat, means for automatically controlling the inflow of liquid in a manner to maintain the suspension at a substantially constant level, and means for controlling the admission of pulp to the container in a manner to maintain a substantially constant ratio of solid matter to liquid in the pulp suspension, said controlling means comprising a reciprocable member having direct mechanical connection with both said mechanisms.

25. In a device of the class described, a container for a liquid suspension of pulp, means for continuously forming a mat of the pulp of the suspension, means for causing the liquid of the suspension to flow through said mat, mechanism responsive to variations in the thickness of the formed mat, other mechanism responsive to variations in the flow of liquid through the mat, means for automatically controlling the inflow of liquid into the container in a manner to maintain the suspension at a substantially constant level, and means for controlling the admission of pulp to the container in a manner to maintain a substantially constant ratio of solid matter to liquid in the pulp suspension, said controlling means comprising a threaded shaft having

- a longitudinal slot and mounted for rotation and for motion along its length, and two gears mounted on said shaft and restrained from motion lengthwise thereof, one of said 5 gears being threaded on said shaft and operatively connected with one of said mechanisms, the other of said gears being constrained to rotate with said shaft by engagement with said slot, and operatively connected with the other of said mechanisms.
26. In a device of the class described, a container for a liquid suspension of pulp, means for continuously forming a mat of the pulp of the suspension, means for causing the liquid of the suspension to flow through the mat, mechanism responsive to variations in the thickness of the formed mat, other mechanism responsive to variations in the outflow of liquid, means for 10 regulating the inflow of liquid in a manner to maintain the suspension at a substantially constant level, and means to control the admission of pulp to the container in a manner to maintain a substantially constant 15 ratio of solid matter to liquid in the pulp suspension, said controlling means comprising a reciprocable member mechanically connected directly to both said mechanisms and responsive to an increase in the thickness of 20 the pulp mat to move the reciprocable member in one direction, and responsive to an increase in the outflow of liquid to move the reciprocable member in the opposite direction.
27. In a device of the class described, a container for a liquid suspension of pulp, means for forming a mat of the pulp of the suspension, means for causing the liquid of the suspension to pass through the mat, 25 means for indicating the freeness of the pulp, said indicating means comprising a rectilinear scale member movable laterally between limiting positions, a rider slidably mounted on said scale member for motion lengthwise thereof, a traveler movable in a direction parallel to the length of the scale member between limiting positions, and means operatively connecting said rider and said traveler; means for measuring the 30 thickness of the pulp mat, means for measuring the outflow of liquid, mechanism controlled by one of said measuring means for imparting motion to said scale member, means for rendering said mechanism inoperative when the scale member reaches either 35 of its limiting positions, another mechanism controlled by the other measuring means for imparting motion to said traveler, and means for rendering said other mechanism 40 inoperative when the traveler reaches either of its limiting positions.
28. In a device of the class described, a container for a liquid suspension of pulp, means for forming a mat of the pulp of the suspension, means for passing the liquid of the suspension through the mat, means for indicating the freeness of the pulp, said indicating means comprising a rectilinear scale member, and a rider slidably mounted for motion relatively lengthwise thereof; 45 mechanisms for jointly controlling the motion of the rider relative to the scale member, one of said mechanisms being responsive to variations in the thickness of the pulp mat, another of said mechanisms being responsive to variations in the flow of liquid through the mat, an operating electric circuit, and means controlled by the movement of the rider relative to the scale member for varying the potential in said circuit.
29. In a device of the class described, a container for a liquid suspension of pulp, means for forming a mat of the pulp of the suspension, means for causing the liquid of the suspension to pass through said mat, and means for automatically indicating the thickness of said mat, said indicating means comprising a hunting member movable from its normal position by change of thickness of said mat, a triode tube having a filament, grid, and plate, a plate-filament circuit including a relay-coil, means controlled by the motion of said hunting member for varying the potential of the grid, thereby varying the current through the relay coil to close the relay or permit it to open, and a motor controlled by said relay to restore said hunting member to normal position.
30. In a device of the class described, a container for a liquid suspension of pulp, means for forming a mat of the pulp of the suspension, means for causing the liquid of the suspension to pass through said mat, and means for automatically indicating the thickness of the mat, said indicating means comprising a hunting member movable from its normal position by change of thickness of said mat, a triode tube having as elements a filament, grid, and plate, a circuit involving certain of said elements and arranged to be closed by motion of the hunting member from its normal position, another circuit involving certain of said elements and a relay responsive to the motion of the hunting member, and a motor controlled by said relay for restoring said hunting member to normal position.
31. The device as set forth in claim 28, but which, in addition, comprises also an electro-responsive recording device connected with said operating circuit.
- In testimony whereof I have affixed my signature.

MILTON O. SCHUR.
